CHAIN OF BAGS

Clarence W. Vogt, Norwalk, Conn.

Application September 4, 1948, Serial No. 47,820

8 Claims. (Cl. 229—53)

1

This invention relates to enwraps and in particular to the assembling of enwraps or bags into a chain or series.

It is an object of the present invention to provide a plurality of enwraps or bags connected into a chain or series so that they may be successively advanced without manually handling of the individual bags or enwraps. It will be obvious that the provision of such a chain is of extreme value in successively advancing bags in order that they may be filled, closed, sealed, etc., by machinery, thus obviating manual handling of the individual bags. Not only does this permit of savings in packaging time and cost but also permits packaging with decreased possibility of contamination which is desired in the case of packaging foods, drugs and similar products.

Another object is to provide a plurality of bags connected into a chain or series without the need of providing chaining means, fastening means or the like, other than such means as may be afforded on bags manufactured in present conventional designs.

A further object is to provide a chain or series of bags in which a portion of the normal closure means provided for such bags may be utilized to detachably chain the bags.

Another object is to provide a plurality of bags connected in multiple chains so that a plurality of bags may be successively advanced simultaneously. Such a chain would be advantageous for use in feeding bags to a filling apparatus having facilities for filling two bags simultaneously.

Other objects and advantages will become apparent from the following detailed description accompanied by the drawings in which:

Figure 1 is a perspective view of a portion of a chain embodying the present invention in which adjacent bags are connected in end to end relationship;

Figure 2 is an enlarged sectional view through a modified form of chain in which two chains of single bags are connected together to permit successive advancing of a pair of bags; and

Figure 3 is an enlarged fragmentary perspective view of a bag adapted to be connected into a chain and provided with a handling element or member to facilitate control of the bag during advancement thereof to filling or closing or sealing apparatus.

The chain illustrated in Fig. 1 comprises one of the simplest forms of chains which can be made in accordance with the present invention. A plurality of bags 1 are shown and in this form

2

the bags are of a plain envelope type in common use and which may be readily made by conventional bag making machines. In making this type of bag a tubular casing of sheet material is formed and cut into lengths suitable for the size of bag to be made. As shown in Fig. 1 one sidewall of the completed bag is cut along a curve whereas the other sidewall may be cut substantially along a straight line so that one sidewall 5 extends beyond the other sidewall in the region of the mouth of the bag to provide a closing flap 2 which may be used to assist in opening the bag and after the bag is filled may be folded over to provide a closure member. If desired the flap 10 may be provided with any suitable adhesive so that it may be adhered to the opposite sidewall of the bag after folding over to seal the completed package. The bag bottom may be closed by folding the casing upon itself and 15 securely joining the folded portion to the bag. The edge of the folded bottom portion is indicated by the numeral 3 in Fig. 1.

As described, it is often customary to provide the flap 2 with an adhesive area either covering 20 the interior surface of the flap or at desired portions therealong so that the flap may be adhered to the bag to close the mouth thereof. When a suitable adhesive material is used for this purpose it is possible to connect the bags into 25 a chain or series so that they may be advanced successively by adhering a portion of an adjacent bag in the chain to the interior surface of the flap 2. For example, when a suitable thermoplastic adhesive material is applied to the flap it 30 may be activated or made tacky by heat and by 35 positioning an adjacent bag in the series in overlapping relation with the flap and the overlapped portions may be adhered together.

In Fig. 1 the numeral 4 indicates an adhesive 40 area or a portion thereof which may be activated to a tacky condition so that the bottom portion of an adjacent bag will be firmly adhered thereto. Thus, by advancing the first bag in the chain, 45 succeeding bags will follow along. When the first bag has been fed to the filling apparatus it 50 may be opened in any suitable manner, such as by the use of vacuum cups to draw apart opposite sidewalls of the bag in the region of the mouth, or by a jet of air directed from the region of the nozzle to separate the opposite bag walls, or by the use of mechanical fingers to enter the mouth of the bag and spread the sidewalls, or in any other desired manner.

After the bag has been filled it may be desirable 55 to separate it from the chain to permit its being

transferred to a suitable conveyor for further handling. In this event the adhesive area 4 which provides the connection between the bag being filled and the next succeeding bag may be heated to soften or reactivate the thermoplastic adhesive which will permit severance of the bag from the chain. It may be desirable, however, to retain the bag in the chain after filling so that the successive bags may be further advanced, for example, to a closing and sealing station at which time the bags may be sealed and removed from the chain.

From this description it will be obvious that considerable savings may be obtained due to the utilization of a plurality of bags connected into a chain for feeding them to filling, closing or sealing apparatus or the like. At present bags are made individually, packed in stacks of individual bags, and generally placed in boxes for shipment. Even the packaging of bags in boxes is an item of appreciable cost to a bag manufacturer. By the present invention the bags may be connected into chains as shown in Fig. 1 and rolled into a roll. Large rolls may be transported with or without the use of wrappings to enclose them and when desired for use may be placed on a spindle and unreeled.

In the case of individual bags bought for packaging, the usual commercial operations for filling the bags involve manually handling the bags from stacks and manually presenting them to the filling apparatus or to a conveyor which passes adjacent the filling apparatus. By the use of the present invention the chains may be fed directly to the filling apparatus with a minimum of expense and effort in handling the bags.

Fig. 2 illustrates a modified form of chain in which individual chains similar to that shown in Fig. 1 are combined by superposing one chain on another and connecting the bags of each chain together. Thus, pairs of bags may be simultaneously removed from the chain and thereafter handled until severance of the pair is desired. The pairs may be secured together in any suitable manner such as by providing portions of the bags to be paired with adhesive areas which may be placed in register and the bags adhered together. For this purpose any suitable adhesive material may be utilized, one example of a satisfactory adhesive being the self-sticking type which will adhere to an area of the same substance but does not adhere to other surfaces. The bags may also be secured together in many other suitable ways. For example, top flaps of bags to be paired may be stapled together or any one of a variety of fastening elements may be utilized.

A desirable form of connection is shown in Fig. 2 which discloses a plurality of bags 11 connected into a series by adhering top flaps 12 thereof to the adjacent bottom portions 13 of adjacent bags such as by the use of an adhesive 14. An identical chain or series formed of bags 15 having their top flaps 16 connected to bottom portions 17 of adjacent bags by an adhesive 18 is placed alongside the previously mentioned chain or series of individual bags with bags of one chain superposed or in register with bags of the other chain. In this position adjacent bags of each series may be paired such as by the use of a tab or handling element 20. To illustrate, the upper margin of the tab 20 may have previously been connected to the bag 11 by an area of adhesive 21. The lower margin of the tab 20 may be coated with an adhesive 22 which may be a

thermoplastic adhesive known as a "delayed action" type, that is, it can be activated by heat to tacky condition and permitted to cool prior to adherence. Thus the area of adhesive 22 may be activated prior to placing the bags 11 and 15 in registry so that when they are placed in registry they may be adhered merely by the application of pressure.

Between the two adhesive areas 21 and 22 the tab 20 preferably has an uncoated central portion 23 which will not be adhered to either bag. This uncoated portion 23 of the tab will serve as a link between adjacent chains and permits spacing of the connected bags. An advantage of this construction is to permit the insertion of handling fingers or other members useful in lifting or transferring the bags. Also, the pair of bags are adapted to be readily supported such as by resting the portion 23 on a horizontal rail of a conveyor or the like.

The member 20 may be made in any desirable manner but it is believed preferable to provide them with their end portions adhesively coated on opposite sides thereof with an intervening uncoated portion 23. Thus, the adhesive materials utilized at opposite ends of the tabs may have different characteristics so that, for example, activation of the adhesive at one end of the tab will not activate the adhesive at the other end of the tab. If a thermoplastic adhesive material is utilized to coat the opposite surfaces of the end portions of the tab these adhesives might be of such a nature that they will have different activation temperatures, one of which may be appreciably higher than the other.

Further, the tab portions may if desired, remain on the bag after filling, closing, or sealing, and in such event it may be desired to make the tabs of such a size that advertising matter can be imprinted thereon. Also, these tabs may be useful for handling the completed package or to facilitate displaying the package on a display rack. If it is desired to retain the tabs on the completed packages the tabs may be severed through the uncoated portions 23 in any suitable manner. It may also be desired to remove the tabs and when a thermoplastic adhesive material is utilized this can be readily done by heating the end portions of the tab to soften or reactivate the adhesive and then peeling or sliding the tabs from the bags. The tabs may also be detachably secured to the bags by a pressure sensitive adhesive having characteristics of high shear strength but which may be readily peeled.

Figure 3 illustrates another modified form of chain similar to that shown in Fig. 1. In this chain the individual bags or tubes, a portion of one of which is indicated by the numeral 25, are of the type in which a length of casing is cut along a straight line so that the sidewalls are of substantially equal length. The bottoms may be closed in any suitable manner. Individual bags may be connected together to form a chain by providing an adhesive area indicated by the numeral 26 on the exterior surface of one sidewall of the bag, preferably near the mouth thereof so that the bag may be adhered to the bottom portion of an adjacent bag. When viewing Fig. 3 the area 26 is disposed on the exterior of the rear side wall of the bag or tube 25. As shown in the drawing the individual bags 25 in the chain may be provided with a member or handling element 27 for use in controlling the bag. For example, the chain may be fed to the filling position and

the bags opened by gripping the handling element 27.

It is also contemplated that the provision of the member 27 may facilitate handling of the bag to advance it either before or after it has been removed from the chain. As shown in Fig. 3 the handling element 27 comprises a tab member of the type shown in Fig. 2 in which one end portion 28 is adhered to the bag 25 and the opposite end portion 29 is provided with an adhesive area 30 on its outer surface, the adhesive area 30 being on the surface of the tab 27 which is directed in an opposite direction from the surface adhered to the bag 25. Also, between the end portions 28 and 29 an intervening portion 31 is provided which is preferably not adhesively coated. To emphasize the fact that the portions 28 and 31 are not adhered to the bag or tube 25, the portion 31 is shown at a distinct angle to the bag wall. Generally the portions of the member 27 will lie adjacent the bag wall extending only slightly outwardly therefrom in normal position.

The adhesive area 30 may be utilized to facilitate gripping of the handling element or in the event the bag mouth is not provided with other sealing means the end portion 29 may be dimensioned and positioned so that it can be folded over the bag mouth to act as a closure strip. If the member 27 is disposed below the bag mouth a suitable distance the walls of the bag mouth may be folded over and for packaging of many materials the use of the member 27 as a sealing strip may be adequate. Obviously the member 27 may be of such size and shape that it will act as a label and completely enclose the top portion of the bag to provide an efficient air-tight or sift-proof seal. For example, if the handling element extends for the full width of the bag or tube the end portion 29 when folded over the bag tube mouth and sealed against itself would provide a sealed area completely surrounding the top and sides of the mouth.

While the drawings show bags connected into chains by securing the mouth end of one bag to the bottom portion of another bag while the bags are in end to end position it will be apparent that many other forms of chains can be provided. For example, it is contemplated that bags may be chained with their transverse side edges overlapped and secured together resulting in a chain which may be fed sideways with the mouths of all of the bags faced in the same direction. Further it is possible to secure the bags together with only portions of their side edges overlapping or with only corner portions of the bags overlapping and secured to provide a chain in which individual bags will move along a line disposed diagonally with respect to the bags. It is generally believed preferable to connect the bags into chains in which the mouth ends of each bag face in substantially the same direction so that the chains may be advanced to a filling position and each bag mouth will be properly presented to the filling nozzle.

Chains or series of bags made in accordance with the present invention may be assembled from any type of bag. The bags illustrated in the drawing are of the envelope type but it will be obvious that almost any other type of bag may be readily utilized. For example, in many instances it is desirable to use bags provided with infolds or pleats along their transverse side edges. This type of bag is desirable since it has the capacity of opening more fully where the nature of the contents to be enclosed make this desirable.

Such bags may also be easier to open or control at the filling station.

The present invention may be readily applied to enwraps or bags or tubes of heat sealable material or having heat sealable liners or heat sealable material disposed around the interior of the bag mouths to permit sealing of the bags or tubes by autogeneously welding or sealing the same.

For example, lengths of tubular casing formed of a heat sealable material may be readily chained for feeding to packaging machinery. If the material of which the bag is made is capable of softening when reheated without damaging the material, it may be possible to detachably connect the bags into a chain without the necessity of applying an additional adhesive. Also, where bags are made of such a material, handling members, tabs, labels or the like may be readily affixed thereto by the use of a thermoplastic adhesive having a lower activation temperature than that of the bag material so that applying or removing of the handling members will not fuse or seal the bag wall. When bags or tubes of heat sealable material having a relatively low fusing temperature are utilized it is preferable to secure handling members and the like with a delayed action type thermoplastic adhesive material since it has the property of remaining tacky after cooling below its activating temperature. Further, the use of a suitable pressure sensitive adhesive may also be desirable to avoid adversely affecting the bag wall. Adhesives of this type are available with satisfactory adhering properties but which may be readily peeled or removed without offsetting, marking or damaging the bag or tube.

It will be understood that the foregoing description of preferred embodiments of the invention is for the purpose of explanation and illustration and numerous variations and modifications may be made without departing from the spirit of the invention.

What I claim is:

- 45 1. As an article of manufacture for use in packaging, a plurality of bags each of which has a closure flap extending beyond the mouth thereof, an adhesive on the inside surface of each of said closure flaps, said bags being disposed in sequence in openable condition with their mouths faced in the same direction, a closure flap only of one bag being in overlapped relation with a bottom portion of an adjacent bag and adhered thereto by said adhesive in position to permit progressive advancement, opening and filling of said bags while so connected, whereby said adhesive may be used to connect said bags in sequence during packaging and to seal said bags when filled.
- 50 2. As an article of manufacture, a plurality of bags each having a side wall thereof extending beyond its opposite side wall in the region of the mouth of the bag to form a flap, and a detachable adhesive bond between at least a portion of that surface of each of the flaps forming a continuation of the inner surfaces of the first mentioned side walls and the outer surface of the same wall of an adjacent bag, said bonds connecting the bags in a chain and being detachable to disengage the flap of one bag from the next adjacent bag.
- 55 3. An article, according to claim 2, wherein said surfaces of the flaps are provided with an adhesive material at least a portion of which forms the detachable adhesive bond.
- 60 4. A bag chain comprising a plurality of bags,
- 65
- 70
- 75

each having an open end, front and back walls and an open closure flap on said back wall at the open end of the bag extending beyond the end of the front wall at said open end, detachable adhesive bonds detachably connecting said bags together in end to end relation with the open end of each bag adjacent to the end of another bag opposite from the open end of said another bag, and with the closure flap, only, of each bag overlapping a wall of an adjacent bag, the flap of one bag being detachably connected to said wall of an adjacent bag by means of the detachable adhesive bond interposed between a portion of the flap and said wall of said adjacent bag.

5. A bag chain comprising a plurality of pairs of bags, each bag having a front wall, a back wall and an open end, said back wall having a closure flap thereon extending beyond the adjacent edge of the front wall, means detachably connecting the bags of each pair to each other with their back walls in opposition and means detachably connecting the closure flaps only of each pair of bags to the opposite ends of bags of another pair to position the bags in end to end relation in two rows in which all of the bags are detachably connected.

6. A bag chain comprising a first series of bags, each having a front wall, a back wall and an open end, means detachably connecting said bags in end to end relation with their open ends facing in the same direction and free from obstruction by the adjacent end of other bags of said series, a second series of bags connected together in the same way as said first series and having their open ends facing in the same direction as the open ends of the first series and means detachably connecting the individual bags of said first series to individual bags of said second series with their back walls in opposing relation.

7. As an article of manufacture, a plurality of bags, each having a sidewall thereof extending beyond its opposite sidewall in the region of the bag mouth to form a closing flap, said bags being arranged in a series with a portion of the bottom of each bag disposed in overlapping relation with a portion only of the inside face of the clos-

ing flap of an adjacent bag and a detachable adhesive bond securing the bottom of each bag to said portion of said flap of an adjacent bag in such a position that said opposite sidewalls are arranged in non-overlapping series to permit opening and filling of said bags while so connected, said adhesive bond permitting detachment of said portion of said flap from the bottom of the bag in overlapping relation thereto.

10 8. An article of manufacture which comprises a plurality of bags, each of which has one of its side panels extending beyond its opposite side panel in the region of the bag mouth to form a closing flap, adhesive material on the inside surface of said closing flap, said bags arranged in a series and having their mouth portions faced in the same direction with a bottom portion of each bag overlapping and secured detachably to a portion only of the flap of an adjacent bag by means of a detachable adhesive bond in such position that the opposite side panels are arranged in non-overlapping series to permit progressive advancement, opening and filling of said bags while so connected, said portion of said flap being detachable from said bottom of the bag to enable said bags to be separated and the open top of a bag to be closed by the detached flap thereon.
